UNITED STATES PATENT OFFICE.

CLINTON LOVELL, OF BOSTON, MASSACHUSETTS, ASSIGNOR TO THE ALBERT NAIL COMPANY, OF NEW YORK, N. Y.

WIRE-NAIL MACHINE.

SPECIFICATION forming part of Letters Patent No. 340,887, dated April 27, 1886.

Application filed September 25, 1885. Serial No. 178,141. (No model.)

To all whom it may concern:

Be it known that I, CLINTON LOVELL, of Boston, in the county of Suffolk and State of Massachusetts, have invented certain new and 5 useful Improvements in Wire-Nail Machines, of which the following is a specification.

This invention relates to machines for making wire nails, and is an improvement on the invention shown in Letters Patent of the 10 United States No. 328,236, granted to N. C. Lewis, October 15, 1885.

The object of the present improvement is to provide means for controlling the lengths of wire after they are severed from the main wire 15 by the cutters, and carrying said lengths positively to the severing and pointing dies below said cutters, so that the lengths of wire will not fall loosely, but be deposited accurately between the severing and pointing dies.

20 To this end the invention consists in improvements, which I will now proceed to describe and claim.

Of the accompanying drawings, forming a part of this specification, Figure 1 represents 25 a side elevation and partial section of a portion of a machine provided with my improvements. Fig. 2 represents a section on the line $x x$, Fig. 1. Fig. 3 represents a partial top view of the portion of the machine shown in 30 Fig. 1. Fig. 4 represents a top view of the entire machine. Fig. 5 represents a section on line $y y$, Fig. 4.

The same letters of reference indicate the same parts in all the figures.

35 In the drawings, a represents the supporting-frame of the machine, which is provided with a rock-shaft, f , having two arms, to which are affixed the cutters $h h$, whereby lengths or sections are cut from two supplying-wires, 40 each section being of the proper length for two nails. The lever e is operated by an oscillating-lever, c , which is pivoted at c' to the frame of the machine, and is connected by a rod, d , with the lever e , as described in the 45 above-named Lewis patent, so that the cutters $h h$ act alternately in cutting off lengths of wire, the lever c being oscillated by a crank, b' , on the driving-shaft working in a slot in the end of the lever. The lever c is connected by 50 rods $i i$ at opposite sides of its pivot with tog-

gle-joints $j j$, which operate the parts or dies k k , whereby the sections of wire cut off by the cutters $h h$ are divided into two parts, and whereby points are formed on both parts, as described in the Lewis patent.

55 Four headers or hammers, m , two for each wire-cutter h , and each pair of severing and pointing dies k , are employed to form heads on the ends of the lengths of wire, as described in the above-named patent. In Fig. 4 I have 60 shown the two hammers at one side of the machine only, those at the opposite side being concealed by the mechanism above them.

Suitable feeding mechanism is employed to move the wire forward after each length is cut 65 off, so as to supply material for the next lengths to be cut, said mechanism being the reciprocating racks $n' n'$, having spring-feeding dogs and devices for reciprocating said racks simultaneously in opposite directions, as in the 70 Lewis patent.

In the machine described in the above-named 75 patent, the lengths of wire after being cut off were allowed to drop loosely upon supporting- rods $i' i'$, situated below the severing and pointing dies.

It has been found that when the machine is rapidly operated the lengths of wire do not fall with sufficient accuracy and certainty to place between the severing and cutting dies. 80

In carrying out my invention I provide means for positively holding the lengths of wire from the time when they are severed until they are in position between the dies and resting on the rods $i' i'$, instead of allowing them 85 to drop loosely from the cutters h , as heretofore.

The wire is introduced by the feeding mechanism into plates or guides N , having slots opening at the bottom, so that the wire entering 90 said slots can move downwardly therefrom.

Latches or detents 88 , fitted to slide in sockets in the frame of the machine, are pressed outwardly by a spring, 12 , (shown in dotted lines in Figs. 6 and 7,) and project into each 95 guide N and under the length of wire therein, so that said length cannot fall of its own weight when severed from the main wire. The spring 12 bears at its central portion on the curved wall of the cavity in the frame, in which 100

said spring is contained, its ends being thus adapted to yield and allow the detents 8 8 to move backwardly.

I I represent arms secured at their lower ends to holders I', which are supported by levers L L pivoted to the frame a, said levers being connected by rods M with the lever c. The motion of the lever c oscillates the levers L L, which move the arms I I up and down. Said arms have hooks 6 at their upper ends, which project over the lengths of wire when the arms I are raised, as shown at the left in Fig. 1. When the arms I are lowered, the hooks 6 bear upon the wire and force it down along the ends of the yielding latches 8, and along the sides of yielding arms 9, below the said latches, said arms being pivoted at 13 to the supporting-frame and pressed outwardly by springs 10 bearing on rods or pins 14, interposed between them and the arms 9, as shown in dotted lines in Figs. 6 and 7.

The latches 8 and arms 9 constitute detents or brakes that bear against the lengths of wire while they are being depressed by the hooks 6 until they nearly reach the supporting-rods i', the lengths of wire being thus prevented

from falling by gravitation, and perfectly controlled while moving from one position to the other.

Springs K, secured to the holders i' and levers L, draw said holders back, so as to press the upper ends of the arms I against the lengths of wire.

The arms I have hooks 7 below the hooks 6, to remove the completed nails from the dies in 35 case said nails stick to the dies.

I claim—

The combination of the cutters which sever the wire-lengths from the main wire, the severing and pointing dies located below the cutters, and means, substantially as described, for holding said lengths during their movement from the cutters to the dies, as set forth.

In testimony whereof I have signed my name to this specification, in the presence of two 45 subscribing witnesses, this 26th day of August, 1885.

CLINTON LOVELL.
